J. H. BAETZ

STANDARD LAMP OF CANDELABRA TYPE

Filed Feb. 17, 1928

ATTORNEY.

UNITED STATES PATENT OFFICE.

JACOB H. BAETZ, OF KITCHENER, ONTARIO, CANADA.

STANDARD LAMP OF CANDELABRA TYPE.

Application filed February 17, 1928. Serial No. 255,065.

My invention relates to improvements in standard lamps of candelabra type, and the object of the invention is to devise a simple and cheap structure which may be easily assembled so that the candle or other like fixture may be carried on a lamp standard with a controlling switch interposed centrally between such fixtures, and also to devise means for supporting a lamp shade over the candles whereby a shade may be adjusted slightly in any direction desired so as to throw the light as required, and it consists essentially of the arrangement and construction of parts as hereinafter more particularly explained.

Fig. 1 is a side elevation showing the upper portion of a lamp standard with my structure carried thereon.

Figs. 2 and 3 are enlarged perspective details of the members which together form the central body containing the controlling switch and supporting at each side thereof the candle fixtures.

Fig. 4 is a plan sectional view through the central body and the candle fixtures connected thereto.

Fig. 5 is a vertical section through the body showing its connection to the upper end of the lamp standard and to the lower end of the shade support.

Fig. 6 is an enlarged detail of the universal joint connection between the shade supporting standard and the upper finial end thereof.

In the drawing like characters of reference indicate corresponding parts in each figure.

1 indicates a lamp standard of usual construction provided at its upper end with a reduced portion 2 over which fits an inverted cupped member 3 secured thereto by screws 4. The upper portion of the inverted cupped member 3 is formed with a central internally threaded orifice 5.

6 is an exteriorly threaded nipple which is screwed at its lower end into the internally threaded orifice 5, the upper portion projecting upwardly from the cupped member 3. 7 and 8 are two members which when secured together form a central body carried by the lamp standard and supporting candle fixtures 9 and 10. The portions 7 and 8 when placed together form a hollow body containing a switch 11 operated by a controlling handle 12 extending through a front orifice 13 in the centre of the member 7. I do not describe the construction of the switch 11 and

its handle 12 in detail as it is an ordinary tumbler type of switch.

The member 7 is provided with upwardly and downwardly extending neck portions 14 and 15 respectively forming half orifices 16 and 17. From each side of these portions extend lateral wing portions 18 and 19.

20 and 21 are edge flanges extending along the upper edge of the member 7 from the half orifice 16 and terminating at the end of each wing 18 and 19. 22 and 23 are flanges 65 extending upwardly from the half orifice 17 along the edge of the lower portion of the member 7 and terminating at the base of each wing portion 18 and 19 to form a half orifice between the extremity of the flanges 20 and 70 22 and 21 and 23.

The member 8 is similarly formed to the member 7 with the exception that at the extremity of each neck portion 14^x and 15^x are formed collar like portions 24 and 25 which 75 are provided with internally threaded orifices 26 and 27.

When the members 7 and 8 are assembled together the neck portions 14 and 15 fit against the corresponding neck portions 14^x 80 and 15^x so that the opposing edge flanges of such neck portions fit one against the other and form an interior hollow containing space for the switch 11. The half orifices of the wings 18 and 19 of both members 7 and 8 85 when fitted together form a complete opening through which the lead wires from the switch 11 extend so as to pass to the light source of the candle fixtures 9 and 10.

The member 7 is provided with orifices 28 90 and at each side of the centre thereof, and the member 8 with correspondingly positioned studs 29 provided with internally threaded orifices 29^x.

30 are screws which pass through the orifices 28 into the internally threaded orifices 29 so as to secure the members 7 and 8 together.

At the lower end of each half opening of the member 8 corresponding to the half openings formed by the wings 18 and 19 of the member 7 are located horizontally extending bosses 31 and 32 each provided with internally threaded orifices 33. 34 is a screw which extends through each candle fixture in- 100 to the internally threaded orifice 33 to secure the fixture thereto.

The vertical edge portions of the outwardly

extending wings 18 and 19 of each member 7 and 8 are slightly concaved so that the candle fixtures fit thereto and when the screw 34 is tightened it holds the fixture in a vertical position.

When the members 7 and 8 are assembled together as above described so as to form a complete body carrying the candle fixtures 9 and 10, such body is screwed onto the upwardly extending projecting portion of the nipple 6 thereby firmly securing such body to the upper end of the lamp standard 1.

35 is an upwardly extending standard rod threaded at its lower end as indicated at 36, such threaded end being screwed into the orifice 26. The standard rod 35 is provided at its upper end with a finial end 37 which is connected to the main body of the rod by a universal joint 38 shown in detail in Figure 6. By this means the upper end or finial on which a shade is supported in the usual manner may be tilted in any desired direction so as to carry the shade horizontally over to any required position.

From this description it will be seen that I have devised a very simple structure for standard lamps of candelabra type which may be readily assembled or disassembled whenever desired, which will be cheap to manufacture and strong and durable in construction.

What I claim as my invention is:—

1. In a standard lamp of candelabra type, the combination with the lamp standard proper provided with an upwardly extending reduced portion, of an inverted cup fitting upon such reduced portion and suitably secured thereto and having a central internally threaded orifice in its upper or base portion, 40 a nipple threaded into such orifice so as to project upwardly therefrom, a hollow body having upper and lower vertical orifices into the lower one of which the aforesaid nipple is adapted to be screwed, a pair of candle fixtures, means for securing a candle fixture at each side of the body, and a shade support-

ing standard extending upwardly from the body centrally between the candle fixtures.

2. In a standard lamp of candelabra type, the combination with the lamp standard proper, of a hollow body divided centrally parallel to its face, each member being provided with an upwardly extending neck portion and laterally extending wing portions, opposing edge flanges extending from the extremity of each neck portion to the extremity of the corresponding wing and along the upper edge of the member, and an edge flange extending from the extremity of the lower neck to the base of the wing to form lateral orifices, a boss formed in the half orifice of one member so as to extend into the half orifice of the opposed member when the parts are secured together, candle fixtures, and a screw extending through each fixture into a corresponding boss.

3. In a standard lamp of candelabra type, the combination with the lamp standard proper, of a hollow body divided centrally parallel to its face, each member being provided with an upwardly extending neck portion and laterally extending wing portions, opposing edge flanges extending from the extremity of each neck portion to the extremity of the corresponding wing and along the upper edge of the member, and an edge flange extending from the extremity of the lower neck to the base of the wing to form lateral orifices, a boss formed in the half orifice of one member so as to extend into the half orifice of the opposed member when the parts are secured together, candle fixtures, a screw extending through each fixture into a corresponding boss, a collar like portion formed at the upper and lower extremity of the neck portions of one member to overlap the corresponding neck portions of the other member, means extending into the collar of the lower neck for securing it to the lamp standard, and a shade supporting standard extending into the collar of the upper neck.

JACOB H. BAERZ.
